CLAIM

The ornamental design for a drinking straw with partial face mask, as shown and described.

DESCRIPTION

FIG. 1 is a front elevational view of a drinking straw with partial face mask showing my new design;
FIG. 2 is a left side elevational view thereof, the opposite side being a mirror image;
FIG. 3 is a fragmentary rear elevational view thereof;
FIG. 4 is a perspective view thereof;
FIG. 5 is a bottom plan view thereof; and,
FIG. 6 is a top plan view thereof.
